UNITED STATES PATENT OFFICE.

FRANKLIN A. LUCE, OF CHICAGO, ILLINOIS.

DESIGN FOR AN APPAREL-BELT.

SPECIFICATION forming part of Design No. 34,682, dated June 18, 1901.

Application filed May 13, 1901. Serial No. 60,122. Term of patent 3½ years.

To all whom it may concern:

Be it known that I, FRANKLIN A. LUCE, a citizen of the United States, residing at Chicago, in the county of Cook and State of Illinois, have invented and produced a new and original Design for Apparel-Belts, of which the following is a specification, reference being had to the accompanying drawings, in which—

Figure 1 is a perspective view showing my new design. Fig. 2 is a sectional view on the line $x-x$ of Fig. 1, and Fig. 3 is a sectional view on the line $y-y$ of Fig. 1.

My invention relates to a new and original design for apparel-belts, and the essential feature thereof resides in an apparel-belt having upon the outer surface of the main or body portion a longitudinally-corrugated appearance and having extending from such longitudinally-corrugated portion two gradually-widening ends that are each divided into a series of faces wider at their outer ends than at their inner ends, said inner ends each merging into one of the corrugations referred to.

Referring to the accompanying drawings, A indicates the belt as a whole, upon the material composing the outer face of which is

formed a series of tucks a , that extend longitudinally of the belt and parallel with each other, such tucks standing out sufficiently to give the belt a longitudinally-corrugated appearance. These tucks a , that impart the appearance of longitudinal corrugations, extend for the entire length of the belt except on its ends B B, which ends, as shown, gradually increase in width from where they leave the main or body portion of the belt. These ends B B are each divided into a series of faces b , each of greater width at its outer end than at its inner end, and each of said narrow inner ends merging into one of the tucks a .

Having described my invention, what I claim as new, and desire to secure by Letters Patent, is—

The design for an apparel-belt, as herein shown and described.

In testimony whereof I have hereunto signed my name to this specification in the presence of two subscribing witnesses.

FRANKLIN A. LUCE.
